MICHAEL LANDI, OF PATERSON, NEW JERSEY.

ATTACHMENT FOR WINDING MACHINES.

Application filed September 2, 1922. Serial No. 585,926.

To all whom it may concern:

Be it known that I, MICHAEL LANDI, a subject of the King of Italy, and a resident of Paterson, in the county of Passaic and State of New Jersey, have invented certain new and useful Improvements in Attachments for Winding Machines, of which the following is a specification.

This invention relates to an attachment 10 for winding machines.

The invention more particularly relates to an attachment for silk winding machines or the like in which silk is made into strands and then wound upon a number of bobbins.

15 This type of machine is well known by those skilled in the art and the purpose of this invention is to provide an attachment for a machine of this character which may be applied in numbers, one for each of the bobbins 20 employed upon the machine and which is adapted to limit the amount of silk or other thread wound upon the bobbin, that is to say when the bobbin becomes fully wound the attachment will operate to bring the bobbin to a stop and thus discontinue the winding of silk or other thread thereon.

25 It is also an important object of the invention that the attachment will not interfere with the normal operation of a winding machine.

30 It is also within the scope of the invention that the attachment be exceedingly simple in construction and inexpensive to manufacture.

35 Other objects will hereinafter appear.

The invention is illustrated by way of example in the accompanying drawings, in which,

40 Figure 1 is a fragmentary view in side elevation of a winding machine and showing the invention applied.

45 Figure 2 is a vertical sectional view of the same taken centrally of one of the bobbins and also showing the supporting frame of the machine for the attachment.

Figure 3 is a group view showing in perspective the different elements constituting the attachment,

50 Figure 4 is a detail perspective view illustrating the manner in which the bobbins are usually turned by the band wheels of the winding machine.

Like reference numerals refer to similar characters.

Referring to the drawings more particularly, F indicates generally the frame of a winding machine, S a shaft which is adapted for driving a plurality of band wheels W, and B the bobbins driven by the band wheels W. Each of the bobbins B is supported by a spindle 10, said spindle being extended through the bobbin and having at its one end a collar or annular enlargement 11 which may be brought into frictional engagement with the associated band wheel W whereby to rotate the bobbin for winding the silk thread or the like thereon. As shown in Figure 2 of the drawings, frame members 12 and 13 extend parallel with the frame F and are positioned forward thereto. From the top frame member 12 there extends inwardly for each bobbin B a pair of arms 14, one of which is shown, and said arms each being formed adjacent its free end with a notch 15 adapted for receiving the ends of the associated spindle 10. Suitable means are usually employed for lubricating the spindle. By supporting the bobbins B in this manner each bobbin is free for vertical movement, and as is apparent upon being raised a slight degree the collars or enlargements 11 will be disengaged from the band wheels W and thus the bobbins will cease to rotate.

In carrying out the present invention there is provided the channel member generally designated by the reference character 15 which has the free edges of its sides turned inwardly as at 16 to provide a guide-way 17. The bridge portion of the channel member is provided herewith with two openings, one of which is adapted for receiving the bolt 18 and the other adapted for receiving the bolt 19. The bolt 18 is extended through a cross frame member 20 and provided with a suitable nut 21 whereby to hold the channel member in the position shown in Figure 2 of the drawings. A wing nut 22 is provided for the bolt 19, the purpose of which will later appear.

An L-shaped bracket 23 is provided and as specifically shown in Figure 3 has its portion 24 longitudinally slotted as at 25, said slot being adapted for receiving the bolt 19.

The portion 24 of the bracket 23 is adapted to slide within the guideway 17 and as is obvious through the means of the bolt 19 this bracket may be adjustably locked within the member 15. The portion 26 of the bracket member 23 has secured thereto a substantially U-shaped casting 27, said casting being secured to the bracket 23 through the means of a screw or the like as at 28, said screw extending through the bridge portion of the casting. The leg portions 29 of the casting 27 curve outwardly with relation to the portion 24 of the bracket 23 and rotatably support between their free ends a roller generally indicated by the reference numeral 30.

When the attachment is properly mounted upon the machine the position of the roller 30 with relation to the associated bobbin B is as shown in Figure 2 of the drawings and the operation of the attachment for accomplishing the purposes of the invention is as follows: The roller 30 is adjusted with relation to the bobbin B so that when the desired amount of thread is wound upon the bobbin, said thread will come in contact with the roller 30. This adjustment of the roller 30 is made through adjusting the bracket 23 by means of the bolt 19 and wing nut 22. In operation the winding machine will turn the bobbins through the band wheels W and upon a bobbin having sufficient winding thereon of a silk thread or the like the roller 30 comes into engagement with said thread and leaves the bobbin so that the driving connection between said bobbin and associated band wheel W is discontinued. The bobbin may now of course be replaced by a new bobbin and the same operation proceeded with. As is apparent substantially any thickness of winding upon each bobbin may be had by adjustment of the associated roller 30.

While I have shown and described the preferred form of my attachment it should be understood that I am aware of the fact that slight modifications may be made by those skilled in the art without departing from the spirit of my invention as indicated by the appended claims.

What I claim is:

1. A bobbin lifting attachment for winding machines of the character described comprising a supporting plate, means whereby the plate may be adjustably secured to the frame of a winding machine, an L-shaped member having its one end portion provided with an elongated slot, said slot extending longitudinally of said portion, a bolt extending through an opening in the supporting plate and also extending through the slot in the last named portion of the L-shaped member, a nut carried by the bolt whereby the L-shaped member may be adjusted with respect to the supporting plate,

and a roller rotatably supported at the outer end of the free portion of said L-shaped member, for the purpose described.

2. A bobbin lifting device for winding machines of the character described comprising a supporting plate, means whereby the plate may be detachably secured to the frame of the winding machine, an L-shaped member having its one end portion provided with an elongated slot, a bolt extending through an opening in the supporting plate and the slot in the last-named portion of the L-shaped member, a nut carried by the bolt whereby the L-shaped member may be adjusted with respect to the supporting plate, a pair of upwardly extending arms formed adjacent the outer end of the other portion of said L-shaped member, and a roller turnably supported between the free end of said arms, for the purpose described.

3. A bobbin lifting attachment for winding machines of the character described comprising a channel plate having the free end of each side portion thereof formed with an inwardly turned flange whereby to provide a guideway passage between said flanges and the bridge portion of said member, means whereby said channel member may be secured to the frame of the machine, an L-shaped member having one portion adapted to slide in the guideway of said channel-shaped member, said portion of the L-shaped member having a longitudinally extending slot, a bolt extending through an opening in the bridge portion of the channel member and through the slot in the last-named portion of the L-shaped member, a nut carried by said bolt whereby the L-shaped member may be adjustably secured upon the channel member, and a roller turnably supported at the free end of the other portion of the L-shaped member, for the purpose described.

4. A bobbin lifting attachment for winding machines comprising a channel-shaped supporting plate, each side portion thereof being formed with an inwardly extending flange whereby to provide a guideway between each flange and the bridge portion of said channel member, a bolt extending through the bridge portion of the channel member and having its head counter-sunk therein, a cross arm carried at the other end of the bolt adapted to be utilized for clamping the channel member upon the frame of the machine, an L-shaped member having one portion slidable in the guideways of said channel member, said portion of the L-shaped member having a longitudinally extending slot, a bolt extended through an opening in the bridge portion of said channel-shaped member and also through the slot in the last-named portion of the L-shaped member, a nut carried by said bolt whereby the L-shaped member may be ad-

justably secured to the supporting channel member, and a roller rotatably supported upon the free end of the other portion of said L-shaped member, for the purpose described.

5. A bobbin lifting attachment for winding machines of the character described comprising a supporting plate, means whereby the plate may be detachably secured to the

frame of a winding machine, an L-shaped bracket member, means whereby one portion of said member may be adjustably secured to the supporting plate, and a roller rotatably supported at the outer end of the other portion of said L-shaped member, for the purpose described.

MICHAEL LANDI.
